(57) CLAIM

The ornamental design for a cosmetic product package, as illustrated and described.

DESCRIPTION

FIG. 1 is a front perspective view of the cosmetic product package showing our new design;

FIG. 2 is a front view thereof;

FIG. 3 is a right side view thereof;

FIG. 4 is a back view thereof;

FIG. 5 is a left side view thereof;

FIG. 6 is a top view thereof; and,

FIG. 7 is a bottom view thereof.

The gray scale shading within the zig-zag pattern represents color contrast consonant with the visual appearance shown in the drawings.

The broken lines are included for the purpose of illustrating the portions of the cosmetic product package that form no part of the claimed design.
